UNITED STATES PATENT OFFICE.

ARTHUR BATES, OF LEICESTER, ENGLAND, ASSIGNOR, BY MESNE ASSIGNMENTS, TO
UNITED SHOE MACHINERY CORPORATION, OF PATERSON, NEW JERSEY, A COR-
PORATION OF NEW JERSEY.

UPPER-SHAPING MACHINE.

1,419,202.

Specification of Letters Patent. Patented June 13, 1922.

Application filed May 31, 1916. Serial No. 100,950.

To all whom it may concern:

Be it known that I, ARTHUR BATES, a subject of the King of England, residing at Leicester, Leicestershire, England, have invented certain Improvements in Upper-Shaping Machines, of which the following description, in connection with the accompanying drawings, is a specification, like reference characters on the drawings indicating like parts in the several figures.

This invention relates to upper shaping machines, and has for an object to provide an improved organization of means for conforming upper materials to the contour of a last or other shoe form. The invention is herein illustrated in its application to the shaping of the uppers of veldtschoen or stitchdown shoes, but it will be recognized that in various novel aspects the invention is not limited to the manufacture of shoes of that particular type.

A feature of the invention consists in a novel organization comprising a flexible member, herein conveniently termed a "wiper", for drawing or wiping an upper to the contour of a form about the end of the form, together with means for controlling the marginal portion of the upper in such manner as to maintain the upper in an unwrinkled condition about the end of the form and to render the flexible wiper effective to draw the upper tightly and smoothly to the contour of the form. The construction shown comprises means for clamping the margin of the upper outspread about the toe end of the form from one side of the toe to the other with yielding pressure permitting the upper to slip at any point or points where the tension produced by the indrawing pull of the wiper tends to become excessive, thus assisting in equalizing the tension and in maintaining the pressure of the wiper uniform on the different portions of the upper which it engages. On stitchdown shoe work, the clamping means illustrated is adapted to shape or mold the margin of the upper to produce an outturned flange characteristic of that kind of work. The machine herein shown is constructed also to pull or stretch the upper over the form by relative movement between the form and the marginal clamping means, and a further feature of

the invention is to be recognized in an organization such as hereinabove set forth including means for pulling the upper over the form.

A further feature of the invention consists in a novel organization of upper pulling means. In this part of the invention important objects in view are substantially to equalize the tension of the upper over different portions of the contour of the form and to foredraw the upper while establishing the correct lines required for the finished shoe. The desired results are effected in the construction shown by means which clamps the marginal portion of the upper yieldingly about the end of the form under such pressure as to permit the margin to slip at points of excessive tension, together with opposite side grippers which engage the upper farther rearwardly at the sides of the form, and operating means for effecting relative movement between the form and the clamping means and the grippers to pull the upper both heightwise and lengthwise of the form at the toe end and at the opposite sides. In this manner the strains on the different portions of the upper are substantially equalized and the entire forepart of the upper is subjected also to a foredrawing tension without relative displacement of parts at the end and the sides such as might distort the line of the tip seam where the shoe is provided with a tip. Such means for pulling the upper over the form, when combined with means for drawing or wiping the upper into conformity to the contour of the form as hereinabove set forth, produces an upper completely shaped over the forepart of the form without substantial differences in the strains applied at different portions of the upper such as might lead to loss of shape in the wear of the shoe, and without wrinkles in those parts of the upper which have been found heretofore particularly difficult to shape in a smooth and satisfactory manner.

The above and other features of the invention, including also a novel construction of upper clamping means and various other details of construction and combinations of parts, will now be described with reference to the accompanying drawings and pointed out in the claim.

Fig. 1 of the drawings is a side elevation partly in section showing an illustrative machine in work receiving position.

Fig. 2 is a view to contrast with Fig. 1, 5 Fig. 2 showing the machine at a certain stage in its operation upon a shoe.

Fig. 3 is a detail view in part sectional side elevation of certain alternative mechanisms for the machine.

10 Fig. 4 is a right-hand elevation of parts shown in Fig. 1.

Fig. 5 is a right-hand elevation of parts shown in Fig. 2.

15 Fig. 6 is a part sectional elevation of the upper part of the machine.

The machine shown comprises a shoe form or last support, herein frequently termed a tread rest, and operating mechanism therefor; a toe clamp or retarder and side grippers, and operating mechanisms therefor by which, in co-operation with the last support, the upper is stretched and adjusted; and a mechanism for manipulating the stretched upper into lasted position about the forepart of the last. These mechanisms will be described in the order enumerated and then their joint operation explained.

The last support 1 has a tread resting face provided with projections to restrain movement of the tread face of the last, or of an innersole, over the same, and said support is mounted to swing upwardly about a fixed pivot 2 located a substantial distance below the shoe and, as shown, under the rear part 35 of the shoe.

The swinging of the last support is effected by connection with the power operating mechanism of the machine. The support is engaged under the ball of the last by a plunger 4 pivoted to the left-hand end of a lever 5 which has a fixed fulcrum at 6 and the forked right-hand arm of which is connected by links 8 and a cross-head 9, Figs. 4 and 5, with a rod 10 which carries an abutment 12 that is adjustable on the rod to provide more or less lost motion between the rod and the last support operating cross-head. This provision is desirable because the rod is also connected, as will be described, with the side grippers and the retarder which should be operated to seize the upper before the support is moved to raise the last.

The last support operating rod 10 has a 55 threaded adjustment in a cross-head 15 which is connected by links 16 with a link 18, Figs. 1 and 2, that has a strap encircling an eccentric 20 on the power shaft 21. The described organization is such that rotation 60 of the eccentric draws down rod 10 and, after the lost motion between abutment 12 and cross-head 9 has been exhausted, rocks lever 5 to move the tread rest and the last upwardly and backwardly about pivot 2.

65 The clamp or retarder comprises two flat

plates 30, 31 which are recessed in their edges toward the last support substantially in V-shape to receive the forepart of the last. The plates are adapted to clamp between themselves the margin of the upper continuously from one side of the toe around the end of the toe to the other side of the toe and frictionally hold the upper so that on a predetermined tension being exceeded at any point or points the upper may slip between the plates to permit relative movement of different parts of the upper in accordance with requirements of different parts of the toe portion of the last over which the upper is being shaped.

The lower retarder plate 30 is rigidly mounted on a table comprising the top of a frame member 32, in which the lever 5 is pivoted. The upper plate 31 is carried loosely on a plunger 35 between a shoulder of which and a collar 36 the plate is confined. The plate is overlaid by a cap 38 the top face of which is convex and fits the concave lower face of the collar so that the retarder plate can tip to adjust itself to the work. A spring 39 encircles the plunger and is confined between the shoulder thereon and a shoulder on the cap plate to maintain the curved faces in contact and a pin 37 rising from the frame member 32 assists in holding the plates 30, 31 in suitable relation and limits tipping of plate 31.

The upper retarder plate is moved down to clamp the margin of an upper introduced between the plates by a lever 40 connected to the plunger 35 and fulcrumed at its right-hand end to a post 42. The rod 10 extends loosely through the lever 40 and is encircled above the lever by a spring 45 through which upper clamping pressure is applied, the tension of the spring being regulated by a nut 44 on the upper end of the rod. A second and weaker spring 46 is confined between the lever and the frame, and the rod has collars 47, 48 which, in the movement of the 110 rod up and down, act respectively to relieve the lever of the pressure of the spring 45 or 46.

It will now be understood that movement is transmitted from the power shaft 21 through rod 10 and spring 45 and connections to operate the retarder to clamp the margin of the upper and that this occurs while the lost motion is being used in the connection of the rod 10 for raising the last support.

The side grippers, Fig. 6, are located to engage the upper at each side of the last in a position appropriate for the application of transverse draft or strain to the upper to 125 which longitudinal draft is applied by relative movement of the last and the retarder. These grippers each comprise an inner jaw formed on a tubular bar 50 that is movable endwise in a gripper guide 52 and is upheld 130

by a spring 54 confined between the lower bearing of the guide and a collar 53 on the bar. The outer jaw 55 is pivoted to the inner jaw and connected by a link to an operating rod 56 which is movable in the tubular bar by a link connection with a cross-bar 60. The cross-bar is pivoted on a longitudinal bar 62 so that it constitutes an equalizer between the two side grippers and it is extended laterally to form handles by which the operator can adjust the forepart of the upper transversely across the last. The longitudinal bar 62 is carried on a vertically movable rod 65, Fig. 1, that carries a sliding sleeve 65' resting on a spring 66 encircling the rod and supported at its lower end by a collar 66' fast on the rod. A lever 70, fulcrumed to the frame, is pivoted to the sleeve and is connected to the link 18 to receive motion from the eccentric 20 and transmit it through spring 66 to pull down the side grippers.

The side gripper guides 52 are pivotally supported on a slide 72, Fig. 6, and are adjustably connected together by a right and left threaded rod 73 by which they can be set for widths of shoes. The slide 72 is mounted on a stationary frame bar 74 that extends longitudinally of the machine and the slide is movable lengthwise of that bar by a screw rod 75 having a knurled head, Fig. 1, to adjust the side grippers toward and from the retarder for lengths of shoes.

The side grippers have an automatic movement toward the toe to foredraw the upper by connections which derive their movement from the same eccentric from which the pulling motion is derived and the last rest lifting movement earlier described. The screw rod 75 has two collars fast on it, the inner one of which constitutes a sliding bearing for the rod in the bar 74. Between the collars is a block to which is connected the lower end of a lever 80 that is connected by a short link 78 to the frame and by a longer upper link to a lever 82 that is fulcrumed on bar 74. The lower arm of the lever 82 is connected by a link 83 to the right-hand end of the vertically movable bar 62 and when the bar is moved downwardly the link and lever arm operate as a toggle to swing the lower end of lever 80 toward the right and move the side grippers forwardly.

The stretched upper is manipulated into lasted position around the toe by drawing it to and wiping it into conformity with the edge of the last bottom in the case of stitch-down shoes by a wire loop 85 or like flexible wiper extending about the forepart and adapted to accommodate itself to the last contour and be tightened hard around the work. The wire loop 85 is shown as attached to the power-operated lever 80, the upper end of which is forked above its op-

erating link, and the loop extends around the forepart of the last, Fig. 2, above the retarder where it operates to draw the upper to the edge of the last.

From the foregoing description it will be understood that the organization of the machine is such that when a last, with or without an innersole on its tread face, is applied to the support or sole rest 1 with the margin of the upper between the retarder plates 30, 31 and the jaws of the side grippers, the lasting loop 85 being in place above the retarder, and power is applied the several mechanisms will be operated as follows:— The retarder plates will yieldingly clamp the margin of the upper around the toe and hold it outspread, the side grippers at about the same time seizing the upper at the sides of the ball. The shoe support will then be rocked about pivot 2 to carry the last upwardly and backwardly to conform the upper to the contour of the top face of the forepart of the last by stretching it longitudinally and transversely of the shoe between the last on the one hand and the retarder and side grippers on the other hand, the retarder giving up stock as required at the points where the greatest strain is effected and the last being moved to a position in which its tread face is above the clamped margin of the upper. In the meantime the side grippers move downwardly and also, through lever 80 and rod 75, are moved forwardly to carry the margin of the upper, and the ends of the tip seam if it is a cap toe shoe, forwardly to balance the forward displacement of the upper over the top face of the last by the pull of the retarder. While the upper is being stretched and conformed to the top face of the last the lasting loop 85 is pulled rearwardly, causing it to adapt itself to the shape of the toe of the last, and it draws the upper to and wipes it into conformity with the edge of the last bottom to form, in a stitch-down shoe, the tuck or crease by which the upper fits the angle formed by the side of the last and the projecting margin of the sole.

I contemplate the use of a stop clutch of any well-known type which will bring the machine to rest with the parts in the position shown in Fig. 2 to allow a toe binding wire to be applied in the crease formed and held by the lasting loop and to be suitably anchored, as for example to a tack located in the heel end face of the shoe. When the machine is restarted the parts are returned to their initial position and the upper is freed from the retarder and grippers to permit the shoe to be withdrawn from the loosened lasting loop and the support 1.

In the modification shown in Fig. 3 the last support 101 is extended rearwardly to support an adjustable heel rest 102 which entirely prevents longitudinal rearward

movement of the last relatively to the last support. The last support is pivoted at 104 upon a bracket 106 projecting from the frame of the machine. The last support is held lightly in contact with the plunger 4 by a spring 105 connecting the support and lever 5. Upon the bracket 106 is also supported a shaft 107 carrying rolls, one of which is seen at 108, over which pass the side portions of the loop 85, each end of the loop being attached to a cross head 110 on the end of a rod 112 guided in a bracket 113 on the frame. The rod passes loosely through an opening in a lever 120 which is pivoted on the frame at 121 and is connected to the sleeve 65' by a link 122. Pinned to the rod 112 is a collar 114 which is arranged to rest upon the lever 120, and confined on the rod between the lower side of the lever 120 and a nut 115 on the end of the rod is a spring 123 which tends to depress the rod relatively to the lever while permitting relative movement between the lever and the rod.

25 The operation of the construction shown in Fig. 3 will be readily understood from the preceding description. It will be noted that in this construction the wire loop 85 is operated by the lever 120 through the yielding connection afforded by the spring 123, and also that the yielding quality of the pull applied to the loop may be varied independently of other means by adjustment of the nut 115.

35 If desired, the upper may be prepared for the operation of the present machine by molding its heel end portion in a special molding operation such, for example, as described in prior United States Letters Patent No. 1,156,897, and in such case the shoe is ready, after the operation of this machine, for the shoe bottoming operations, with the aid sometimes of more or less shank lasting. It will be understood that on stitchdown 45 shoe work, as illustrated, the clamping means shapes or molds the margin of the upper about the toe into an outturned flange for attachment to the sole or insole.

It will be recognized that the foregoing disclosure includes a novel method for use in the making of shoes, which is not claimed herein since it forms the subject-matter of a divisional application, Serial No. 423,630, filed on November 12, 1920.

55 Having described the invention, what I claim as new and desire to secure by Letters Patent of the United States is:

1. A lasting or pulling-over and lasting machine for veldtschoen work comprising 60 means for positioning a last, a retarder for engaging the margin of an upper upon the last substantially continuously from one side of the toe end to the other and constructed and arranged to permit the different parts of the margin to move relatively

on the application of unequal tensions to the upper at different points around the toe, power-operated means for producing relative movement between the last positioning means and the retarder to conform 70 the upper to the top of the last, and a wire loop wiper adapted to be applied loosely about the edge of the shoe at the forepart and to effect in the lasting of each shoe a drawing of the upper towards and a wiping 75 thereof into conformity with the edge of the last bottom, together with power-operated mechanism for relatively operating the wiper and the last positioning means to effect said wiping. 80

2. A lasting or pulling-over and lasting machine comprising means for positioning a last, a retarder for engaging the margin of an upper upon the last substantially continuously from one side of the toe end 85 to the other and constructed and arranged to permit the different parts of the margin to move relatively on the application of unequal tensions to the upper at different points around the toe, means for producing 90 relative movement between the last positioning means and the retarder to conform the upper to the top of the last, and a wire loop wiper adapted to be applied loosely about the edge of the shoe at the forepart 95 and to effect in the lasting of each shoe a drawing of the upper towards and a wiping thereof into conformity with the edge of the last bottom, together with power-operated mechanism connected with the free 100 ends of the loop wiper and organized to operate the wiper to effect said wiping and to come to rest holding the upper in position for the application of a toe binder.

3. A machine for shaping shoe uppers having, in combination, a form or last support, a retarder constructed and arranged relatively thereto to clamp the forepart of an upper from one side of the toe around to the other side, means for relatively moving 105 the retarder and said support to stretch the upper and conform it to the top face of the form, a loop wiper mounted to be applied around the toe, and means for operating the wiper to draw the upper into conformity 110 with the contour of the edge of the form.

4. A machine for shaping shoe uppers having, in combination, a last support, a retarder arranged relatively thereto to clamp an upper around the toe and comprising 120 upper and lower flat plates arranged to hold the upper between their opposed flat faces, said plates being mounted for relative closing and opening movements, one of said plates being also mounted for tipping movement relatively to the other to adapt the retarder to differences in the thickness of the stock between said faces, and means for relatively operating the retarder and the last support to stretch the upper. 125 130

5. A machine for shaping shoe uppers having, in combination, a form or last support, a retarder comprising plates constructed and arranged to clamp the margin 5 of an upper around the toe, grippers constructed and arranged to seize the upper at the sides of the ball, and means for moving the form and the retarder and grippers relatively to stretch and shape the upper and 10 for simultaneously moving the grippers forwardly toward the retarder.
6. A machine for shaping shoe uppers having, in combination, a tread rest, a stationary retarder for engaging the upper at 15 the toe, side grippers, and connected operating mechanisms for moving the tread rest upwardly and backwardly from the retarder and for simultaneously moving the side grippers downwardly and forwardly.
- 20 7. A machine for shaping shoe uppers having, in combination, a tread rest, a side gripper mechanism comprising a gripper support and grippers mounted thereon and extending adjacent to opposite sides of the tread rest, and connected operating mechanisms for relatively moving the rest and the gripper support to stretch the upper and for moving said support to carry the grippers bodily lengthwise of the shoe.
- 30 8. A machine for shaping shoe uppers having, in combination, a tread rest, upper margin engaging means, a flexible loop wiper, and connected operating mechanisms to effect stretching of the upper and operation of the loop wiper, said mechanisms including yielding means allowing the wiper to adapt itself automatically to varying sizes of shoes.
9. A machine for shaping shoe uppers 40 having, in combination, a tread rest, upper margin engaging means, a flexible loop wiper, and connected operating mechanisms to effect stretching of the upper and operation of the loop wiper, said margin engaging means being constructed and arranged 45 to allow the upper to be pulled therefrom under tension as required during the upper stretching operation and the wiping operation.
- 50 10. A machine for shaping shoe uppers having, in combination, means to clamp the margin of the upper around the toe, a flexible loop wiper, and operating mechanism organized to move the last upwardly and 55 backwardly from the clamping means until the tread face of the last is above the clamped margin of the upper and to pull the loop wiper backwardly for drawing the upper to the edge of the last bottom.
- 60 11. A machine for shaping shoe uppers having, in combination, means to clamp the upper around the toe, a flexible loop wiper, and power-operated mechanism organized to move the last upwardly and backwardly from 65 the clamp until the tread face of the last is above the clamped margin of the upper and to pull the loop wiper backwardly for drawing the upper to the edge of the last bottom and to come to rest holding the upper in position to be bound adjacent to the wiper, 70 said mechanism operating to loosen the loop wiper and open the clamp when the machine is restarted.
12. In a machine of the class described, the combination with a last tread support 75 pivotally sustained near the rear of the last, of means for engaging the forepart of the shoe upper, and means engaging the tread support in a location substantially opposite to the forepart of the shoe to rock the support about its pivot in the direction to stretch the upper between the last and the upper engaging means.
13. In a machine of the class described, the combination with a last support, of a 80 retarder comprising a stationary table, a retarder plate mounted on the table and having a U-shaped edge toward the last support, a second retarder plate adjacent to the first and having a similarly shaped and arranged edge, and a guiding rod secured to the table and engaging the second plate to permit the latter to tip and adapt itself to the thickness of different portions of the work.
14. In a machine of the class described, the combination with a last support, of a retarder comprising two plates to clamp the toe of the upper, and an operating mechanism comprising a member having a yielding 90 connection with the retarder to clamp the upper and a lost motion connection with the last support to move the last during continuous movement of said member in one direction.
15. In a machine of the class described, the combination with a last support, side grippers and means for relatively moving the support and grippers to stretch the upper, of means for adjusting the grippers longitudinally of the last, and operating mechanism acting through the adjusting means to impart foredraw movement to the grippers.
16. In a machine of the class described, the combination with a last support arranged 105 to support a last bottom downward and side grippers, of connected operating mechanisms for moving the last support upwardly and simultaneously moving the side grippers bodily toward the toe end of the last.
17. In a machine of the class described, the combination with a last support, side grippers and a toe wiper, of connected mechanisms for simultaneously moving the side grippers forwardly and moving the wiper 110 rearwardly.
18. A machine for conforming uppers to lasts having, in combination, a last support, means for seizing an upper on a substantially continuous line around the toe, operat- 120
- 130

ing means to effect pulling of the upper and to hold it under tension out from the edge of the last bottom, and a flexible loop wiper adapted to engage the upper around the toe 5 where it is smoothly stretched and to draw the tensioned upper to the edge of the last, the upper holding means being adapted to give up stock under tension to the action of the wiper and the flexible wiper being 10 adapted to accommodate itself automatically to the contour of the last edge.

19. A machine for conforming uppers to lasts having, in combination, a last support and upper seizing means constructed and arranged for relative movement to stretch an 15 upper over the top face of the toe of a last and to hold the margin thereof outward from the edge of the last, and a flexible loop wiper arranged to engage the upper around the toe 20 where it is smoothly stretched and to draw the tensioned upper to the edge of the last bottom and hold it while it is fastened.

20. A machine of the class described having, in combination, means for clamping the 25 margin of an upper substantially continuously round the end of a shoe form from one side of the form to the other, means for effecting relative movement of said clamping means and the form to pull the upper over 30 the top of the form, a flexible member adapted to extend round the end of the tensioned upper, and means for operating said flexible member to draw the upper into lasted position, the clamping means being constructed 35 to permit the margin of the upper held thereby to yield inwardly toward the form as the upper is drawn to the form by said flexible member.

21. A machine of the class described having, in combination, a pair of clamping plates 40 for clamping the margin of an upper in outspread condition round the end of a shoe form from one side of the form to the other, means for effecting relative movement of said 45 clamping plates and the form to pull the upper, a flexible member adapted to extend round the end of the upper held in tensioned condition by said plates, and means for pulling said member rearwardly to draw the 50 upper to the contour of the lateral periphery of the form, said plates being constructed to permit the margin of the upper to slip between them as the upper is pulled by said member.

55 22. A machine of the class described having, in combination, means for clamping the margin of an upper round the end of a shoe form, power operated means for effecting relative movement of said clamping means 60 and the form to pull the upper, a flexible member adapted to extend round the end of the upper held in tensioned condition by said clamping means, and means automatically operative in time relation to other parts 65 of the machine to pull said flexible member

rearwardly for conforming the upper to the contour of the form.

23. A machine of the class described having, in combination, means for clamping and pulling an upper at the end of a shoe form, a 70 flexible member adapted to extend round the end of the upper held in tensioned condition by said clamping means, and yieldable means for operating said flexible member to draw the upper yieldingly into conformity 75 to the contour of the form.

24. A machine of the class described having, in combination, means for clamping the margin of an upper round the end of a shoe form, means for holding said clamping means 80 substantially stationary in clamping engagement with the upper, means for moving the form relatively to said stationary clamping means to pull the upper, a flexible member adapted to extend round the end of the upper, and means for operating said member to draw the upper into lasted position while the margin is held by said clamping means.

25. A machine of the class described having, in combination, means for clamping the 90 margin of an upper round the end of a shoe form, means for moving the form relatively to said clamping means in a direction to stretch the upper with a component of lengthwise movement away from the clamping means to pull the upper outwardly from the end of the form, a flexible member adapted to extend round the end of the tensioned upper, and means for operating said member to draw the outwardly pulled upper 100 into conformity to the contour of the form. 95

26. A machine of the class described having, in combination, means for clamping the margin of an upper round the end of a shoe form, means for effecting relative movement 105 of said clamping means and the form to pull the upper over the top and outwardly from the end face of the form, a flexible member adapted to extend round the end of the upper, and means for operating said member 110 to draw the upper to the end face of the form, the clamping means being constructed to permit the margin of the upper to yield inwardly toward the form in response to the pull of said member. 115

27. A machine of the class described having, in combination, upper clamping means comprising a pair of clamp members constructed to engage the margin of an upper substantially continuously round the end of a shoe form from one side of the form to the other and to hold the margin in outspread condition, means for effecting relative movement of said members and the form heightwise of the form to pull the upper over the 120 top and outwardly from the end face of the form, and means for engaging the upper held under tension by said members and drawing it into conformity to the lateral periphery of the form, said clamping means 125 130

comprising mechanism automatically operative to permit the margin of the upper to slip between the clamp members both in the pulling of the upper heightwise of the form and as it is drawn inwardly to the contour of the form.

28. A machine of the class described having, in combination, clamping means comprising co-operating plates arranged to 10 clamp the margin of an upper in outspread condition round the end of a shoe form, grippers for engaging the upper at the rear of said plates, and means for effecting relative movement between the form and said 15 grippers and clamping means to pull the upper and for moving the grippers forwardly toward the clamping means.

29. A machine of the class described having, in combination, means for clamping the 20 margin of an upper round the end of a shoe form, grippers for engaging the upper at the rear of said clamping means, means for moving the form relatively to said grippers and clamping means to pull the upper while 25 the clamping means is substantially stationary, and means for moving said grippers to draw the upper forwardly toward the clamping means as it is pulled.

30. A machine of the class described having, in combination, means for clamping the 30 margin of an upper round the end of a shoe form, means for holding said clamping means substantially stationary in clamping engagement with the upper, grippers for 35 engaging the upper at opposite sides of the form at the rear of the clamping means, means for moving the form in a direction to cause the upper to be pulled by the grippers and the stationary clamping means, and 40 means for moving the grippers in substantially the opposite direction to increase the pull at the sides and for moving them also forwardly to foredraw the upper.

31. In a machine of the class described, 45 the combination with shoe positioning means, of grippers for engaging the upper at opposite sides of the shoe, means for supporting said grippers for bodily sliding movement lengthwise of the shoe, and operating means for moving said grippers in a 50 direction transverse to the plane of the shoe bottom to pull the upper and for moving them also along said supporting means toward the toe of the shoe in the course of the 55 upper pulling operation.

32. A machine for shaping an upper to the contour of a shoe form having, in combination, means for supporting the form bottom downward to permit the operator to 60 view the upper over the top of the forepart, means for clamping the margin of the upper in outspread condition round the toe end of the form, means for effecting relative movement of said supporting and clamping

means to pull the upper, a flexible member 65 adapted to extend round the end of the upper held in tensioned condition by said clamping means, and means for operating said flexible member to draw the upper into conformity to the contour of the form round 70 its toe end.

33. A machine for shaping the upper of a stitchdown shoe on a shoe form having, in combination, means for supporting the form bottom downward to permit the operator to 75 view the upper over the top of the forepart of the form, means for clamping the margin of the upper in outspread condition round the toe end of the form, means for effecting relative movement of said supporting and 80 clamping means to pull the upper over the top of the form and outwardly from the end face of the form, a flexible member adapted to extend round the end of the upper held in tensioned condition by said clamping 85 means, and means for operating said flexible member to draw the upper to the edge of the bottom face of the form, said clamping means being constructed to mold the margin of the upper into an outturned flange by its 90 clamping action on said margin.

34. A machine of the class described having, in combination, means for supporting bottom downward a shoe form with an upper thereon, means for clamping the margin of 95 the upper in outspread condition round the end of the form, said clamping means comprising a substantially stationary lower plate over which the margin of the upper is to be outspread and an upper plate movable to 100 clamp said margin, and means for effecting relative movement of said supporting and clamping means to pull the upper.

35. A machine of the class described having, in combination, means for clamping the 105 margin of an upper round the end of a shoe form, means for effecting relative movement of said clamping means and the form to pull the upper, a flexible member arranged to extend round the end of the form in engagement with that portion of the upper which is subject to the pull of the clamping means, and means for operating said member in the course of the relative pulling movement of the clamping means and the form to draw 110 the tensioned upper into conformity to the 115 contour of the form.

36. A machine of the class described having, in combination, means for clamping the margin of an upper round the end of a shoe 120 form, means for effecting relative movement of said clamping means and the form to pull the upper over the top of the form, a flexible member adapted to extend round the end of the form in engagement with that portion of the upper which is subject to the pull of the 125 clamping means, and power operated means for operating said member in time relation

to the relative movement of the clamping means and the form to draw the upper into conformity to the contour of the form.

37. A machine of the class described having, in combination, a flexible wiper adapted to extend round the end of a shoe form, means for operating said wiper to draw an upper inwardly round the end of the form into conformity to the contour of the form, and means for clamping the margin of the upper free from wrinkles on a substantially continuous line round the end of the form and for holding the upper under tension between said clamping means and the form during the operation of the wiper.

38. A machine of the class described having, in combination, a flexible loop wiper adapted to extend round the end of a shoe form, means for operating said wiper to draw an upper inwardly round the end of the form into conformity to the contour of the form, and means for clamping the margin of the upper yieldingly round the end of the form to hold it against a determinate pull of the wiper and to permit the margin to slip in response to the pull of the wiper at points of excessive tension.

39. A machine of the class described having, in combination, means for clamping the margin of an upper on a substantially continuous line round the end of a shoe form from one side of the form to the other side, a flexible loop wiper adapted to extend round the end of the upper, and means for operating said wiper to work the upper inwardly into conformity to the contour of the form while the margin of the upper is under the control of said clamping means.

40. A machine of the class described having, in combination, means for clamping the margin of an upper on a substantially continuous line round the end of a shoe form and for pulling the upper heightwise of the form while giving up stock from the clamped margin at points of excessive tension, a flexible loop wiper adapted to extend round the end of the upper, and means for operating said wiper to draw the upper inwardly to the contour of the form while the margin is yieldingly held by the clamping means to permit it to slip in response to the pull of the wiper at points of excessive tension.

41. A machine for shaping the upper of a stitch-down shoe on a shoe form having, in combination, means for clamping the margin of the upper outspread round the toe end of the form in a plane substantially parallel to the plane which the outturned flange of the upper is to occupy in the completed shoe and for pulling the upper heightwise of the form by relative movement between the form and said clamping means, a flexible wiper adapted to extend round the end of the upper, and means for operating said wiper to draw the

upper inwardly to the contour of the form and to crease the upper along the bottom edge of the form, said clamping means being constructed to mold the margin of the upper to produce an outturned flange by its clamping action on said margin. 70

42. A pulling-over machine having mechanism for working an upper under substantially uniform tension over the different parts of an unsymmetrically shaped last toe comprising a sole rest, means for moving the sole rest in a direction to force the last into the upper, side grippers, and means arranged to remain substantially stationary during said movement of the sole rest and constructed and organized to clamp the upper in outspread condition on a substantially continuous line around the toe and hold the upper from slipping while it is drawn under a predetermined tension substantially uniformly over the high and low parts of the toe by the movement of the last relatively to the clamp and the grippers and when such tension is exceeded on any portion or portions of upper extending over a high part of the toe to give up stock under such tension to cover the high parts of the toe as the operation proceeds. 80

43. A pulling-over machine having, in combination, a sole rest, side grippers, means for clamping the upper on a substantially continuous line around the toe organized to hold the margin of the upper outspread from the lateral periphery of the last during relative movement of said clamping means 95 and the last until a predetermined tension on the upper is exceeded and then to give up stock under such tension at any point or points round the toe where the predetermined tension is exceeded whereby the upper may be drawn over the entire top face of an unsymmetrical toe under substantially uniform tension, and means for relatively moving the sole rest and last on the one hand and the grippers and clamping means 100 on the other hand to produce the tensioning of the upper. 110

44. A pulling-over machine having, in combination, a sole rest, side grippers, a vertically stationary clamping plate arranged in substantially parallel relation to the sole rest to have the toe of the upper outspread over it, a clamping member guided for movement in a direction substantially perpendicular to said plate to clamp the outspread upper on said plate, and connected mechanisms to close the grippers, depress said member to clamp the toe of the upper and operate the sole rest to move the last to tension the upper over the last. 115

45. A pulling-over machine having, in combination, a sole rest, a toe clamp comprising a plate arranged to extend lengthwise of a shoe substantially parallel with the sole rest and having a toe recess, a clamp- 130

ing member shaped similarly to the plate at its inner edge, means for yieldingly operating the clamping member to seize and frictionally hold the upper on a substantially continuous line around the toe of the last, and means for relatively operating the sole rest and the clamping means unyieldingly to effect frictional pulling of the upper and to locate the clamping plate and the tread face of the shoe in predetermined relation.

46. A pulling-over machine having, in combination, a sole rest, side grippers, a toe embracing plate, a member co-operating with the plate to clamp the upper on a substantially continuous line around the toe, a toe presser, and operating means to cause the clamping member to clamp the upper and to force the presser transversely of the tread face of the toe of the last.

47. A pulling-over machine having, in combination, a sole rest, grippers arranged relatively to the rest to engage the upper at opposite sides of the forepart, means to clamp the upper in outspread position around the toe, and mechanism to close the grippers and the clamp and to operate the sole rest to move the last to effect the pulling of the upper.

48. A pulling-over machine having, in combination, a sole rest, grippers arranged relatively to the rest to engage the upper at opposite sides of the forepart, means to clamp the upper in outspread position around the toe, and mechanism to close the grippers and move them substantially perpendicularly to the sole rest and relatively to the clamp and also to operate the sole rest to move the last relatively to the grippers and the clamp.

49. In a machine of the class described, a pair of clamp members for clamping the margin of an upper in outspread condition round the end of a shoe form, a tread rest, and operating means for moving one of said members relatively to the other to clamp the upper and for moving the tread rest to cause the upper to be pulled by the clamping means, said operating means comprising a member yieldingly connected to the movable clamp member and positively connected to the tread rest and through which operative movement is imparted to said clamp member and tread rest.

In testimony whereof I have signed my name to this specification.

ARTHUR BATES.
